(57) **CLAIM**

The ornamental design for an adapter, as shown and described.

DESCRIPTION

FIG. 1 is a perspective view of the adapter of the present invention connected to the cord and plug;

FIG. 2 is a top view of the adapter of the present invention;

FIG. 3 is a side view of the adapter of the present invention;

FIG. 4 is a bottom view of the adapter of the present invention;

FIG. 5 is a front view of the adapter of the present invention; and,

FIG. 6 is a back view of the adapter of the present invention. The broken lines showing the cord and plug in FIG. 1 are included for the purpose of illustrating environmental structure only and form no part of the claimed design.
